(57) **CLAIM**

The ornamental design for a combined drawer divider and organizer, as shown and described.

DESCRIPTION

FIG. 1 is a perspective view of a combined drawer divider and organizer in a closed configuration showing the new design;

FIG. 2 is a perspective view of the combined drawer divider and organizer of FIG. 1 in an extended configuration;

FIG. 3 is a front view of the combined drawer divider and organizer of FIG. 2;

FIG. 4 is a rear view of the combined drawer divider and organizer of FIG. 2;

FIG. 5 is a right side view of the combined drawer divider and organizer of FIG. 2;

FIG. 6 is a left side view of the combined drawer divider and organizer of FIG. 2;

FIG. 7 is a top view of the combined drawer divider and organizer of FIG. 2; and

FIG. 8 is a bottom view of the combined drawer divider and organizer of FIG. 2.

FIG. 9 is a perspective view of a combined drawer divider and organizer in a closed configuration showing the new design;

FIG. 10 is a perspective view of the combined drawer divider and organizer of FIG. 9 in an extended configuration;

FIG. 11 is a front view of the combined drawer divider and organizer of FIG. 10;

FIG. 12 is a rear view of the combined drawer divider and organizer of FIG. 10;

FIG. 13 is a right side view of the combined drawer divider and organizer of FIG. 10;

FIG. 14 is a left side view of the combined drawer divider and organizer of FIG. 10;

FIG. 15 is a top view of the combined drawer divider and organizer of FIG. 10; and,

FIG. 16 is a bottom view of the combined drawer divider and organizer of FIG. 10.

(Continued)

The broken lines in the figures depict portions of the article that form no part of the claimed design.
